UNITED STATES PATENT OFFICE.

CHARLES D. MOSHER, OF NEW YORK, N. Y.

STEAM-BOILER.

No. 876,477.

Specification of Letters Patent.

Patented Jan. 14, 1908.

Application filed December 17, 1906. Serial No. 348,299.

To all whom it may concern:

Be it known that I, CHARLES D. MOSHER, a citizen of the United States, residing at New York, in the county of New York and 5 State of New York, have invented certain new and useful Improvements in Steam-Boilers, of which the following is a specification.

This invention concerns the construction 10 and location of superheaters in steam-boilers of the water-tube type with reference to the main boiler-structure, and the purpose of the invention is to secure for the superheater a most advantageous location in regard to the 15 temperature of the gases which come in contact with it while at the same time securing increased durability and permanency and increased ease of repair.

Of the accompanying drawings, Figure 1 20 represents a longitudinal vertical-section showing a superheating-boiler constructed according to my invention. Fig. 2 represents a front elevation thereof, partly in section.

25 The same reference characters indicate the same parts in both views.

In the drawings, 10 and 11 are parallel upper and lower transverse water-drums connected by an inclined group of water-tubes 30 12, 12, to which are preferably imparted such curvatures as will enable the tubes to be withdrawn and replaced through a row of plug-holes in the front shell of the drum 10 which are provided with removable covers 35 13. These covers are here shown in the form of screw-plugs, but any suitable style of cover or filler may be used.

14 is a longitudinal horizontal steam-and-water drum parallel with the planes of the 40 tubes 12 and connected with the upper water-drum 10 by a short uptake pipe 15, and with the lower water-drum 11 by a longer downtake pipe 16. In a boiler of considerable width I prefer to provide a 45 plurality of the steam-and-water drums 14, and have shown two such drums in Fig. 2, having similar connections with the drums 10 and 11 and having their steam-spaces joined by branch steam-pipes 17 into a common steam-pipe 18, the branch pipes taking 50 steam from the drums 14 through longitudinal dry-pipes 19.

20 is the furnace-chamber located underneath the front portion of the water-tube 55 group and passing its flaming gases upwardly across said portion into an upper interme-

diate gas-chamber 21 located beneath the steam-and-water drums 14 and the roof of the boiler setting. A gas-baffle 22 extends across the tube-group at right-angles from 60 the bridge-wall 23 for guiding the gas-current, and a second baffle 24 in the rear of the first one extends part-way across the tube-group from a vertical baffle-wall 25 which leads downwardly from the upper drums 65 and casing-roof to the group of tubes 12. Thus the gases are guided from chamber 21 in a downward return path across the tubes and around the lower edge of baffle 24, from which they pass again upwardly across the 70 tubes to a rear gas-chamber 26 and out through the stack intake-opening 27.

In the intermediate gas-chamber 21 above the main group of tubes 12 I locate the superheater composed of two parallel drums 28, 29, 75 connected by an inclined group of tubes 30 which are curved for the same purpose and in the same manner as the main tubes 12, and are adapted to be inserted and withdrawn through rows of holes in the drums 80 28, 29, which are located opposite the ends of the tubes and provided with screw-plugs 31, there being one row of plug-holes in each drum so that the tubes may be inserted and withdrawn either from the front or the rear 85 of the superheater. The manner of withdrawing superheater-tubes is indicated by dotted lines in Fig. 1. When the tubes are withdrawn in a forward direction they pass out over the upper transverse water-drum 10 90 through doors 32 in the front wall of the boiler-casing, and are adapted to be passed on either side of the short uptake-pipes 15, the arrangement being such that a plurality 95 of the superheater-tubes in both vertical and horizontal directions may be withdrawn through any one plug-hole. When the superheater tubes are withdrawn rearwardly through the drum 29 they may be passed out through the stack inlet-opening 27 or 100 through any opening located in a similar position in the rear casing-wall.

It will be noted that the forward superheater-drum 28 is supported on the upper side of the upper water-drum 10 while the 105 lower superheater-drum 29 is supported in or on the rear baffle-wall 25, and the mounting of both drums may be of a substantial and permanent character, since the curvature of the tubes provides for taking up all 110 expansion strains, and, owing to the manner of construction of the superheater, it will sel-

dom be necessary to remove the drums for the purpose of repairing any part of the superheater.

A permanent open connection exists between the dry-pipe 19 and the lower superheater-drum 29 by way of vertical pipes 33 extending from the dry-pipes down through the bottoms of the steam-and-water drums 14 to the superheater-drum 29, and a second open connection exists by way of a vertical pipe 34 extending upwardly from the upper superheater-drum 28 to the steam-pipe 18. When superheated steam is desired, the branches 17 from the dry-pipes may be shut off by means of valves 35 therein and then the steam passes from the dry-pipes 19, down through the pipes 33, into the lower drum 29 of the superheater, thence through the superheater-tubes 30 where it becomes superheated by the furnace-gases, to the upper superheater-drum 28, and thence through the pipe 34 to the steam-pipe 18. I do not limit myself to a single passage of the steam through the superheater as other arrangements may be effected without departing from the principles of construction herein described. The gases which impinge on the superheater have been partially cooled by contact with the forward ends of the boiler-tubes 12, but are still hot enough to impart a substantial degree of superheat to the steam, and after leaving the superheater they are further cooled down by passage across the rear portions of the boiler-tubes. When saturated steam is wanted the valves 35 are opened and the steam-pipe 18 then takes steam through the branches 17 direct from the dry-pipes 19. In such a case, there being no flow of steam to carry off the heat imparted to the superheater-tubes, it is desirable to flood the superheater with water, and for this purpose I provide the following feed-water connections. 36 are the main feed-water pipes, each having a branch 37 entering the forward end of one of the steam-and-water drums 14 and extending along the bottom thereof to a down-turned end or outlet-nozzle 38 directed into the downtake-pipe 16, and a second branch 39 extending over the roof of the boiler-setting and downwardly into the lower superheater-drum 29. The two branches of each feed-water pipe are provided with stop-valves 40, 41. When the superheater is in use as a superheater only, the main boiler-feed branch 37 is opened, but when the superheater is to be flooded, the second branch 39 of the feed-pipe is also opened and then the feed-water flows in parallel through both branches to the boiler and superheater respectively, making of the superheater, for the time being, a secondary vaporizer which discharges its steam mainly through the pipe 34 into the main steam-pipe 18. The water level will be substantially the same in the boiler and

in the superheater connections since the steam pressure is the same for both, and both are fed by a common water-pipe branching in parallel to the respective destinations.

I claim:—

1. A superheating-boiler comprising a main evaporating-structure having water-drums and connecting tubes and a steam-outlet, and a superheater connected with said outlet and composed of two drums one of which is supported on one of said water-drums, a connecting group of steam-tubes, and a series of holes formed in one of the drums opposite the ends of the tubes and having removable covers, the arrangement being such that a plurality of the superheater-tubes may be withdrawn through each hole.

2. A superheating-boiler comprising a main evaporating-structure having water-drums and connecting tubes and a steam-outlet, and a superheater connected with said outlet and composed of a pair of drums one of which is supported on one of said water-drums, a series of curved tubes connecting said drums, and a row of holes formed in one of the drums opposite the ends of the tubes and having removable covers, each hole being adapted for the withdrawal of a plurality of said tubes.

3. A superheating-boiler comprising a main evaporating-structure, a boiler-casing inclosing the same and having an opening for the withdrawal of superheater-tubes, and a superheater overlying the evaporating-structure within the boiler-casing and including a drum having a series of openings provided with covers, and a group of steam-tubes connected with said drum and withdrawable through said openings in the drum and in the casing.

4. A superheating-boiler comprising a main evaporating-structure, a boiler-casing inclosing said structure and having openings in opposite walls for the withdrawal of superheater-tubes, and a superheater overlying said evaporating-structure within the boiler-casing and composed of two drums, each having a series of holes in its wall provided with removable covers, and a group of tubes connecting said drums and withdrawable in opposite directions through said holes and through the respective openings in the walls of the boiler-casing.

5. A superheating-boiler comprising upper and lower water-drums connected by a group of inclined water-tubes, a steam-drum surmounting the upper water-drum, a boiler-casing, and a superheater located within said casing between the boiler-tubes and the steam-and-water drum, and comprising a drum-structure having openings for the withdrawal of tubes, removable covers for said openings, and a group of superheater-tubes

connected with said drum-structure and withdrawable between the levels of the upper water-drum and the steam-and-water drum, through said openings and through an opening in the boiler-casing.

6. A superheating-boiler comprising upper and lower transverse water-drums connected by a group of inclined water-tubes, a longitudinal steam-and-water drum surmounting the said structure and having uptake and downtake connections with the respective water-drums, and a superheater mounted in the space between the water-tubes and the steam-and-water drum and comprising a drum supported on the upper water-drum, a second drum supported at a remote point, and a group of steam-tubes connecting said superheater-drums.

7. A superheating-boiler comprising upper and lower transverse water-drums connected by a group of water-tubes, a steam-and-water drum surmounting said structure and having uptake and downtake connections with the respective water-drums, gas-baffles for leading the furnace-gases in a sinuous path across the group of water-tubes, a baffle-wall extending between said group of tubes and the steam-and-water drum, and a superheater located in the gas-space above said group of water-tubes and comprising a drum supported on the upper water-drum, a second drum supported on the baffle-wall, and a

group of tubes connecting the said superheater-drums.

8. A superheating-boiler comprising forward and rear transverse water-drums and connecting water-tubes constituting a main evaporating-structure, a longitudinal steam-and-water drum surmounting said structure and having uptake and downtake connections with the respective water-drums, a superheater located between the main evaporating-structure and the steam-and-water drum and comprising forward and rear superheater drums and a connecting group of tubes, steam connections extending upwardly from the respective superheater-drums and communicating with the interior of the steam-and-water drum, valve mechanism for causing the boiler-steam to pass either through the superheater or directly out from the steam-and-water drum, and feed-connections including a main feed-pipe having branches leading into the main boiler and superheater respectively, and provided with stop valves.

In testimony whereof I have hereunto set my hand in the presence of two subscribing witnesses, the 12th day of December, 1906.

CHARLES D. MOSHER.
